ANNIE K. BRENNAN, OF PHILADELPHIA, PENNSYLVANIA

COMBINED CORSET AND BRASSIÈRE

Application filed July 21, 1924. Serial No. 727,186.

The improved combined corset and brassière is intended to give what is known as the "straight figure", that is, one in which the curvatures of the female figure are minimized so that it will appear approximately flat at the portions of the body where these curves would ordinarily appear. These natural curvatures are increased when the muscles of the lower abdomen are relaxed, or fat is accumulated upon it. They are also enlarged by any accumulation of fat upon the back of the body below the waist, and upon the nates. The regulation of the pressure upon these portions of the body is a very delicate problem because of the injury that ensues if too great pressure is imposed on any organ that would be injured by it. A heavy pressure upon the small of the back, or a downward pressure of the abdomen, are both of this character. The nates, indeed, do not contain any organ harmed by pressure, but the pressure upon them must be downward in order to secure the required "straight" effect, that is, the flatness desired for the back of the figure. The corset must be "easy", that is, must accommodate itself readily and without discomfort to the movements of the wearer, and cause her no fatigue when worn continuously for a lengthy period.

In my improved corset, especially when combined with the brassière, the pressure is carried slightly obliquely between the back below the waist line and the upper part of the nates to the middle and lower part of the abdomen, thus giving a slightly upward as well as an inward pressure upon these parts of the abdomen, and a slightly downward as well as inward compression upon the upper part of the nates. The portions of the corset lying over the abdomen and the nates are of non-elastic fabric, stiffened by vertical bones, so that an even compression and flat appearance are given to these parts.

Figure 1 is a view of the inside of the corset, off the wearer and extended. Figure 2 is a similar view of the outside of the corset. Figure 3 is a view of the front of the combined corset and brassière, on the figure. Figure 4 is a side view of the same. Figure 5 is a rear view of the same.

In these drawings, in Fig. 1 a welt is shown as extending around all the edges of the elastic panel or gore, in Fig. 2, this welt is shown as extending across the top and bottom of it only, and in Fig. 3 as extending across the bottom of it only. It is possible to make the device in any of these forms. The drawings Figs. 3, 4, and 5 are merely sketches in outline and are not intended to do more than to indicate the position of the corset on the body. It will be noted that in Fig. 4 the upper and lower edges of panel 10 are not shown as parallel. This usually occurs through the unequal stretching of the elastic material of the gore when on the wearer; Fig. 4 showing the garment on the wearer, while Figs. 1 and 2 show it as laid out flat.

The corset is composed of a front panel (6) and a back panel (13), both of inelastic material, and two wide hip gores (1) and (10) of elastic material. Each of these gores has the up and down edge joined to the back panel, slanting inwards toward the upper edge of the gore. The panel (6) has the skirt (7) and the panel (13) has the skirt (14) extending downward below the line of the lower edges of the panels (6) and (13), and each of these skirts is provided with a pair of garters (3), (3), and (16), (16), that are provided with the stocking clasps (4), (4), and (17), (17), respectively. These garters may serve to aid in limiting the distance the corset can work upward. The garters are placed on the inside of skirts (7) and (14) and are secured by the stitched squares (2), (2) and (15), (15), respectively. The brassière has the bodice (22), which is secured at its lower edge by fastenings (23), (25), (25) to the top edge of the corset, and has the suspenders (20), (20) adapted to pass over the shoulders. This brassière aids in preventing the corset from working downward, and in conjunction with the other means described above, helps to position it properly upon the body of the wearer. The brassière opens and has hooks and eyes for fastening at the back.

The panels (6) and (13) being of equal width at top and bottom, each will extend across the body of the wearer horizontally.

The top of these gores and of the panel (6) run on a straight line, but the line of the upper edge of the panel (13) runs at an angle with this line, owing to the slope of the gore (10), when the corset is laid out open as in Figures 1 and 2. This panel (13) is fastened to the gore (1) by the fasteners (11), (11) and (5), (5). These elastic gores pass over the hips and the hip bones extend sufficiently forward to keep undue pressure of the front panel off the softer parts of the abdomen; and as the lower portion of the panel (6) rests against the strong pelvic bones, the non-elastic fabric is limited by these two strong parts in its inward compression upon the softer parts of the abdomen above, since the increase of pressure upon these softer parts by the slipping up or down of the corset is prevented in several ways.

The inward bend of the front of the female figure at the lower part of the abdomen, in conjunction with the slant given to the corset when on the wearer by the narrowing of the tops of the gores 1 and 10, and the recession of the hip bones at the part of the body covered by the lower part of these gores, will make the perimeter of the lower edge of the corset slightly less than it would be if this edge were pushed upward on the body. These conditions tend to keep the corset from riding up, sinking down, or wrinkling. The resiliency of this lower edge is increased by the welt (30), so that it will stretch much less readily than the middle portions of the gore, and its pull will be much more forcible, so that while the middle portions of the gore are readily stretched out over the increased perimeter of the body above this point, this will be hard to stretch, and will therefore exert a downward pull, thus preventing completely the riding up of the corset. As this pressure is upon the firm, strong pelvic bones, it is not harmful. The upper part of the corset tends to rise, owing to its shape, which is somewhat that of an inverted funnel, when worn; and so tautens and flattens the front of the corset, the bottom of which is held down by the anchoring action of the welt, 30, which causes the lower edge of the corset to form, practically, an elastic belt that, passed around the body, and encircling the lower portions of the pelvic and hip bones, has a less perimeter than it would have if moved upward on the body; and is thus positioned positively by these bones which are very strong and practically immovable relatively to each other. The upper part of the corset to some degree moreover, is held up by the brassière. The cover (12) protects the body from the pressure of the hooks and eyes (11), (11), and (5), (5). The bones (8), (8), (8) and (9), (9), (9), are inserted vertically in the panels 6 and (13) of the corset.

I claim:

1. The combination in a combined corset

and brassière, of a brassière portion, and a corset portion comprising a front portion of non-stretchable material, of such width as to extend substantially between the hip bones at the bottom and of such width as to cover the pelvic bone, a back portion of non-stretchable material and elastic side gores interposed between said front and back portions, and secured thereto, one of these lines of juncture being provided with cooperating fastening means on one of the gores and on one of said portions, each of said gores being narrower at the top than at the bottom and having a welt at the lower edge, said gores being of such extent that their welts will lie slightly below the curved part of the hip bones, the position of the gores being such that when in an applied position, the point of juncture of the welt to the front and back portions of the corset is substantially on a level with the lower part of the pelvic bone in front and the upper part of the nates at the back.

2. In a corset and brassière, the combination with the brassière of a corset of the flexible type comprising in combination a front panel of non-stretchable material, said panel being of sufficient width to extend substantially across the abdomen of the intended wearer, from one hip bone to the other, and of sufficient length to cover with its lower portions the pelvic bones of the intended wearer, a back panel of non-stretchable material, and two elastic side gores interposed between said panels, one of said gores and one of said panels being provided along the line of juncture between the said panel and gore with cooperative fastening means, each of said gores being narrower at the top than at the lower edge and each gore being provided with a welted lower edge, the points of juncture of the welted edges of the gores to the front panel being positioned to lie at a level with the pelvic bones of the intended wearer, and the points of juncture of the said welted edges with the back panel being positioned to lie at the upper part of the nates, the resistance to stretching of the welted lower edge being greater than that of the other parts of the gores thereby producing a more forcible girdling pull along the line following said welted edges, and across the panels between these edges, than is produced by the portions of the gores above said welted edges.
